UNITED STATES PATENT OFFICE.

FREDERICK W. KRANZ, OF GENEVA, ILLINOIS.

VIBRATION INSTRUMENT FOR BONE AUDITION.

Application filed March 29, 1923. Serial No. 628,683.

REISSUED

To all whom it may concern:

Be it known that I, FREDERICK W. KRANZ, a citizen of the United States, and a resident of Geneva, in the county of Kane and State of Illinois, have invented certain new and useful Improvements in a Vibration Instrument for Bone Audition; and I do hereby declare that the following is a full, clear, and exact description of the same, reference being had to the accompanying drawings, and to the numerals of reference marked thereon, which form a part of this specification.

This invention relates to means by which a person who is deaf or partially deaf to ordinary air vibration may be made to hear by means of vibrations conducted through his bones.

An object of the present invention is to produce an instrument for use in the investigation of the hearing through the bones by people who are deaf to ordinary air vibration. The instrument, however, can also be used to investigate bone audition in cases where the air audition is normal.

It is a further object of this invention to provide an instrument of the sort indicated which will itself produce very little vibration in the air, so that it is available for investigations of the sort just mentioned and also for investigations of the hearing of lower animals, fish and the like.

It is a further object of the invention to provide an instrument by which alternating electric current either of a constant period or of the character of the usual telephone currents may be translated into mechanical vibration which can be transmitted to the bones of the subject.

It is a further object of this invention to provide an instrument of the kind indicated which shall produce vibrations of small amplitude but large force.

It is a further object of the invention to provide an instrument of the sort indicated whose efficiency will not be materially diminished by pressing the instrument against the person of the subject.

Other and further important objects of this invention will be apparent from the disclosures in the specification and the accompanying drawings.

The invention (in a preferred form) is illustrated on the drawings and hereinafter more fully described.

On the drawings:

Figure 1 is a top plan view of one form of my invention.

Figure 2 is a side view, partially in section, of the same.

Figure 3 is a section upon the line 3—3 of Figure 2.

Figure 4 is a central section of another form of the invention.

Figure 5 is an end view of the form shown in Fig. 4.

As shown on the drawings:

The instrument includes an iron core 10 having a central member 11 and pole pieces 12 which are turned in toward said central member, so as to leave a small air gap. The central member 11 carries a winding 13 which is supplied with direct current in any convenient way. If desired, instead of the winding 13 supplied with direct current, the central member 11 may be a permanent magnet.

A bridge piece 14 is secured across the frame 10 above the air gap. This bridge piece is of any elastic non-magnetic material such as brass or hard rubber or the like. It is spaced away from the magnetic frame 10 by spacer blocks 15 of non-magnetic material. In the center of its under face it carries a spool 16 secured in any desired manner and extending down into the air gap. This spool is of non-magnetic material such as porcelain, hard rubber, or the like. Preferably also it is of insulating material in order that Foucault currents may not be created therein. A winding 18 upon this spool is held in place by flanges 19 and 20. The center of the spool is hollow in order to surround the upper end of the middle member 11 of the magnetic frame 10. As illustrated, the upper end of the hollow in the spool is closed to make a solid floor for connection with the bar 14. It will, however, be obvious that any method for connecting the spool to the bar may be used.

From the upper surface of the bar 14 in the center, that is, opposite the middle of the spool 16, goes a rod 21 which supports

a disk 22, preferably of hard rubber in or-
der that it may be pressed against the per-
son of the subject under investigation with-
out discomfort. The leads of the winding
18 are provided with a flexible portion 23 in
order that these leads shall not interfere
with the motion of the winding 18.

In the form of the device illustrated in
Figures 4 and 5, a permanent magnet 30 has
10 its pole pieces surrounded by windings 31.
These windings and the permanent magnet
are enclosed within a hard rubber casing 32
and the leads from the windings 31 are
brought out of the small end of this casing
15 as shown at 33; all of this structure being
closely similar to that of the usual telephone
receiver. Instead of a diaphragm, as in the
usual telephone receiver, a bar 34 of mag-
netic material is placed across the open end
20 of the casing 32 in close proximity to the
pole pieces of the magnet 30. This bar is
made of a thickness considerably greater
than that of a telephone diaphragm, in or-
der that when the instrument is pressed
25 against the hearer, the distance from the bar
34 to the pole pieces 31 shall be altered only
slightly. The bar is firmly secured in place
in any desired manner; for example, it may
be fastened by screws 35 to a ring 36 and
30 the ring screw-threaded onto the casing 32.
From the center of the bar 34 rises a rod 21
similar to the rod 21 in the other form of
device and ending in a disk 22 of suitable
material similar to the disk 22 already de-
35 scribed.

In the use of the form of the device
shown in Figures 1 to 3, alternating current
is introduced through the leads 23 into the
winding 18. This current may be of a fixed
40 period such as would be obtained from a
vacuum tube oscillator used in connection
with an amplifier if desired. The fixed pe-
riods may be adjusted in the usual way by
variable condensers or inductances. The
45 alternating current introduced into the leads
23 may, if desired, come from the receiving
set of a wireless telephone outfit. Or, if de-
sired, it may be a current from the receiv-
ing instrument of an ordinary wire form of
50 telephone. Any other form of alternating
current, which corresponds to sounds that it
is desired to investigate, may be used, no
matter what sort of apparatus is needed to
produce this alternating current. The alter-
55 nating current flowing in the coils 18 in the
midst of the magnetic field produced by the
coil 14 or by the permanent magnet will
cause strong impulses to be given, first in
one direction and then in the other to the
60 wires 18 and so to the spool 16. There will
thus be exerted a thrust first up and then
down against the bar 14 which will be trans-
mitted through the rod 21 to the disk 22.

If this disk is pressed against the head of
65 the person whose hearing is being studied so

that the pressure is transmitted to the mas-
toid bone, the vibration produced by the
thrusts just described will be transmitted to
the mastoid bone and so through the bones
of the head to the internal ear. The instru-
ment may, however, be pressed against the
hearer's person at any other point where
the bony structure comes near enough to the
surface to give a firm support for the pres-
sure. For example, it may be applied to
70 the shin bone or to bones of the head other
than the mastoid bone, or to the teeth. The
result is that vibrations are communicated
to the bones of the hearer and so to his ears.
Because of the narrow shape of the bar 14,
75 the vibrating system in the instrument has
but little surface in contact with the air.
Very little vibration in the air itself will
therefore be set up. For this reason, when
the instrument is used in connection with a
80 telephone receiving device and a microphone
such as are frequently used in outfits for en-
abling deaf people to hear, the tendency of
the outfit to sing or howl will be much less
than with such outfits as heretofore made.
85

In the form illustrated in Figures 4 and 5,
the operation is very similar. Instead,
however, of the magnetic field producing a
thrust first in one direction and then in the
other upon a coil, the alternating current in-
90 troduced through the leads 23 to the wind-
ing 31 causes variations in the field and so
a varying attraction on the elastic bar 34
and this bar will vibrate. The vibrations
are transmitted by the rod 21 and disk 22
95 to any selected surface of the hearer's body
and so to his bones in the way already ex-
plained.

In pressing the instrument against the
person of the hearer, the bar 34 will be
100 slightly deflected toward the pole pieces of
the magnet 30, but the bar is made of suffi-
cient thickness so that this deflection is not
large enough to change the efficiency of the
instrument. This rigidity of the vibrating
105 member allows the air gap between it and
the magnetic pole pieces to be made small,
with a consequent gain in the amount of
force exerted on the vibrating member.

I am aware that numerous details of con-
struction may be varied through a wide
range without departing from the principles
of this invention, and I therefore do not
110 purpose limiting the patent granted other-
wise than necessitated by the prior art.

I claim as my invention:

1. In an apparatus for translating alter-
nating currents into mechanical vibrations,
means for producing a magnetic field, a bar,
means for causing vibration of said bar by
the combined action of said magnetic field
and said alternating currents, the area of
said bar in contact with the air being small
125 enough to minimize vibrations of the air
caused by said vibrations of the bar, a disk,
130

and a rod connecting said disk to said bar.
2. In a device of the class described, a magnetic circuit having an air gap, means for producing a constant flux through said circuit, a winding located in said air gap, means for producing an alternating current in said winding, means for transmitting the mechanical vibrations set up by the interaction between said alternating current and said flux, said transmitting means including

a bar across the axis of said winding, a disk, and a rod connecting said disk to said bar.

In testimony whereof I have hereunto subscribed my name in the presence of two subscribing witnesses.

FREDERICK W. KRANZ.
